(57) **CLAIM**

The ornamental design for a holder for devices, as shown and described.

DESCRIPTION

FIG. 1 is a left front top perspective view of our new design for a holder for devices;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

Dash-dash broken lines illustrate portions of the holder for devices that form no part of the claimed design. The dash-dot-dot-dash broken line depicts a boundary and forms no part of the claimed design.
